UNITED STATES PATENT OFFICE

167,386

TOY PAINT SET

Morton R. Berman, Brooklyn, N. Y.

Application November 30, 1951, Serial No. 17,578

Term of patent 7 years

(Cl. D34—15)

To all whom it may concern:

Be it known that I, Morton R. Berman, a citizen of United States of America, residing at Brooklyn, New York, in the county of Kings and State of New York, have invented a new, original, and ornamental Design for a Toy Paint Set, of which the following is a specification, reference being had to the accompanying drawing, forming part thereof.

In the drawing

Fig. 1 is a top view of a toy paint set, showing my new design;

Fig. 2 is a sectional view thereof on line 2—2, Fig. 1, and

Fig. 3 is a side view thereof.

I claim:

The ornamental design for a toy paint set, substantially as shown.

MORTON R. BERMAN.
